Rich'd C. Manning
ATTORNEY

UNITED STATES PATENT OFFICE.

ROBERT GILLHAM, OF KANSAS CITY, MISSOURI.

CABLE RAILWAY.

SPECIFICATION forming part of Letters Patent No. 336,561, dated February 23, 1886.

Original application filed April 27, 1885. Serial No. 163,682. Divided and this application filed November 16, 1885. Serial No. 182,938. (No model.)

To all whom it may concern:

Be it known that I, ROBERT GILLHAM, a citizen of the United States, residing at Kansas City, in the county of Jackson and State 5 of Missouri, have invented certain new and useful Improvements in Cable Railways; and I do hereby declare that the following is a full, clear, and exact description of the invention, which will enable others skilled in the art to 10 to which it appertains to make and use the same, reference being had to the accompanying drawings, forming a part of this specification.

The object of my invention is to prevent 15 the slot-rails in cable railways from being thrown out of position or wedged toward each other by outside pressure, the results of which have been to vary the width of the slot and interfere with the cable-grip, and to afford 20 means for convenient adjustment of said rails at the required distance apart when a variation from their true position is discovered.

An application is now pending in the United 25 States Patent Office, filed April 27, 1885, Serial No. 163,682, of which this application is a division, and in which are the following claims not claimed in this application, viz:

"In a cable railway tube, the combination of 30 the concrete forming said tube, with perforated transverse strengthening plates or yokes, substantially as specified.

"In cable railways, the combination of the 35 slot-rails, a lug upon the supporting device for said rails, an adjusting-rod attached to the slot-rail, and also in the lug, and suitable nuts on said rod and on opposite sides of the said slot-rail, adapted to be operated as shown and described."

In cable railways a pavement of any description laid between the track-rails and slot- 40 rails exerts a pressure upon the latter in proportion to its capacity for expansion or from the manner in which it is laid, and also that due to the passage of loaded wagons over the pavement.

When wood pavements are used, their expansion under the conditions of moisture, it 45 will be readily seen, has an effect to vary the position of the slot-rails, which is readily counteracted by my invention; and it consists 50 in the means for adjusting the slot-rails laterally to meet the change of position, and pre-

serve the requisite width of slot, as herein-after set forth and claimed.

In the drawings, Figure 1 is a plan view of a portion of a cable railway taken on the plane 55 of the yoke. Fig. 2 is a transverse view of the cable railway. Fig. 2^a is a detail view of the adjusting devices as seen in Fig. 2, and showing the nuts on opposite sides of the slot-rails. Fig. 3 is a plan view of the yoke-beam. 60

Similar letters of reference indicate corresponding parts.

A A represent the yoke of a cable railway.

a a are the transverse openings through the yoke A.

B B is the yoke-beam; b b, the transverse openings through the yoke-beam B. b' are bolts securing yoke A to beam B.

C C are the slot-rails.

c c are flanges on slot-rails C.

c' are bolts which pass through the flanges c c, and through the flanges a' of yoke A, securing the slot-rails to the yoke.

c² is the slot.

D D are the adjusting rods or bars.

d d is a nut on the end of rod D which extends through the slot-rail.

d' is a nut on the rod D, and on the opposite side of slot-rail to nut d.

E E are lugs on the upper surface of yoke A.

e e is a nut on the end of rod D which enters the lug E.

e' is a notch or countersink in the lug E to admit the nut e.

I I are the longitudinal adjusting-strips on 85 either side of the slot-rails C C.

M is a nut-wrench.

In the construction of my invention I first make a suitable transverse perforation through the slot-rails C, slightly below the slot c², and 90 in a vertical line with the center of yoke A. I then form upon the upper horizontal surface of the said yoke A, between the slot-rails and the track-rails and stringer-chair, and at a convenient distance from the slot-rails for the 95 proper working of the devices, a lug, E, and perforate the said lug in the direction of the slot-rails, slightly inclining the perforation in an upward direction. Upon the outer and perforated end of the lug E, I make a notch 100 or countersunk seat, e', which receives the nut e and prevents it from turning. I then

make a rod, D, of a suitable length to be attached to the lug E, and also to the slot-rails, and upon one end cut a screw-thread, to which the nut d' is fitted and turned a suitable distance thereon to permit said end to pass through the perforation in the slot-rails. The said screw-threaded end of rod D is then inserted in the perforation in the slot-rails, the nut d' bearing against the outer side of said rail and the nut d fitted to the said end of rod D from the inner side of said rails, securing the rod thereto. The opposite end of the rod D is also provided with a screw-thread, and is first bent downwardly at an angle a suitable distance away from the nut d', and passed through the perforation in the lug E, and slightly beyond the said lug, and the nut e fitted thereto.

The adjusting-strips I are made of any suitable material, and in depth to extend from the flange c of the slot-rail, upon which it rests to the horizontal surface of the said rails. The strips I are cut in the desired lengths to reach from one yoke to an adjoining yoke, and form a continuous outer covering to the sides of the slot-rails, this giving greater lateral strength to the same, and are beveled upon the surface which fays against the said slot rails, as seen in the drawings.

In the operation of the adjusting-rod D, when it is found necessary to vary the position of the slot-rails C laterally, the adjusting-strip I is first removed and tapered to the requisite degree, or a strip of the requisite dimensions made to put in its place. The removal of strip I exposes the nut d' on the rod D, which nut is on the outside and in contact with the slot-rail. The slot-rails C C are then thrown slightly away from each other by releasing the nut d', or allowed to come nearer to each other by releasing the nut d on the said rod D, which nut d is on the inner side of the slot-rails, the nuts c' holding the slot-rails

to the yoke A being first loosened, if necessary, and the said nut d turned to the right or left, as the positions of the slot-rails are found to vary from their relation respecting the width of the slot between the opposite slot-rails. 45

The position of the slot-rails may be readily varied without necessitating the removal of the pavement or entering the tube, for the purpose to accomplish which I use a nut-wrench, M, suitably bent, which I introduce from without through the slot c' between the slot-rails, and which wrench engages with the nut d on the end of bolt D. 50

The advantages of my invention are found of great importance in cable railways, and obviate the disadvantages arising from the compression or variation of the slot-rails referred to, and an increased rigidity is given laterally 60 to said rails, thus more easily resisting lateral pressure.

I do not limit myself in the invention to the precise construction shown; but,

Having fully described my invention, what I claim as new, and desire to secure by Letters Patent, is—

1. In cable railways, the combination of the slot-rail, a lug provided with a countersink, as described, and arranged upon the supporting device for said rails, an adjusting-rod attached 70 to the slot-rails and also to the lug, and suitable nuts on said rod and on opposite sides of the said slot-rail, for the purpose described.

2. The combination, with the slot-rails, of an adjusting-strip, as and for the purpose specified. 75

In testimony whereof I have hereunto set my hand in the presence of two subscribing witnesses.

ROBERT GILLHAM.
